UNITED STATES PATENT OFFICE.

THOMAS J. KERWIN, OF CHICAGO, ILLINOIS, ASSIGNOR TO EDMUNDS & JONES CORPORATION, A CORPORATION OF NEW YORK.

ELECTRIC PULL SWITCH.

Application filed February 23, 1922. Serial No. 538,499.

To all whom it may concern:

Be it known that I, THOMAS J. KERWIN, citizen of the United States, residing at Chicago, in the county of Cook and State 5 of Illinois, have invented certain new and useful Improvements in Electric Pull Switches; and I do hereby declare the following to be a full, clear, and exact description of the invention, such as will enable 10 others skilled in the art to which it appertains to make and use the same.

My invention relates to electric switches and in its general aspects aims to provide a simple, cheaply constructed and easily 15 wired switch adapted for normally maintaining an open circuit and for closing the circuit upon movement of its operating member in one direction.

In using signal lamps for various purposes, such as the so-called stop lights now employed at the rear of automobiles, it is customary to have the circuit to the lamp or other signal normally open and to have this circuit closed by the movement of an 20 operating switch member which is normally held in its circuit-opening position by a spring. For such purposes, it is desirable that the closing of the circuit by the switch should be effected upon a predetermined 25 movement of the operating member and that this operating member should be permitted to move considerably further without effecting the contacts and without overstraining any operative part of the switch. 30 Furthermore, it is highly desirable that such a switch should be substantially sealed against the entrance of moisture, dust or mud, that it should be durable but inexpensive, and that the needed connections to the circuit should readily be made from the 35 exterior of the switch.

My present invention aims to provide a switch construction meeting these requirements and one which might be equally suitable for other uses where the operative condition of a circuit is to be altered by the movement of an operating member which is 40 yieldingly urged at all times towards a predetermined position. More particularly, my

invention aims to provide a switch for this 50 purpose in which the switching member comprises a resilient contact member adapted by its own resiliency to bridge across the wire terminals of the switch, and in which the opening of the circuit is effected by interposing an insulating element between one 55 end of the contact arm and another portion of the switch. It also aims to provide an unusually simple and effective mounting for such an insulating element, desirably in the 60 form of a stem projecting slidably through a wall of the casing; aims to provide a simple mounting for the spring which continually urges the stem towards its circuit-opening position, aims to provide simple 65 means for preventing the operating member from rocking or tilting out of its proper position, and aims to provide simple means for insulating the switch terminals from each 70 other and from the casing of the switch. 75 Still further and also more detailed objects will appear from the following specification and from the accompanying drawings, in which

Fig. 1 is an elevation of a pull switch embodying my invention.

Fig. 2 is a plan view of the same.

Fig. 3 is a bottom view of the same.

Fig. 4 is an enlarged plan view of the 80 switch with the cover plate removed.

Fig. 5 is a vertical and longitudinal section through the switch, taken along the line 5—5 of Fig. 4.

Fig. 6 is a transverse section taken along the line 6—6 of Fig. 4.

Fig. 7 is a perspective view of the insulating contact lifter and of the guide pin secured to the latter.

Fig. 8. is a plan view showing the overlapping insulating base members of the 90 switch together with the two circuit terminals and the resilient contact strip mounted on the same.

In the embodiment of the drawings, the housing of the switch consists in an elongated metal casing of substantially rectangular transverse cross-section, which casing desirably has its main portion formed from a

single piece of sheet material and has at each side of its upwardly directed mouth an ear 1, the two ears being disposed substantially in a common plane. As a closure for this 5 main casing portion I provide a cover plate 2, desirably having its side edges shaped to conform to those of the two ears 1 and secured to both of the ears by eyelets 3 extending through alined perforations in the ears 10 and cover plate and clinched over both thereof. When both eyelets are thus inserted, they hold the cover in a tightly closing position and also afford perforations for the screws such as a switch is commonly fastened to a suitable support, such as the bottom 15 of the floor of an automobile.

Seated on the bottom 4 of the casing is an insulating base which desirably consists of a lower plate 5 shaped to abut against the 20 lateral and end walls of the casing so as to form an insulating lining for the bottom of the casing, and a narrower insulating plate 6 superposed on this bottom plate 5. Extending through both of these insulating 25 plates are a pair of screws 7 and 8, each of which extends through a considerably larger perforation in the bottom of the casing and each of which has a pair of nuts 9 threaded thereon outside of the casing. In each case 30 an insulating washer 10 is disposed between the upper nut and the bottom of the casing so that one of the circuit wires 11 or 12 can readily be clamped by the upper nut against this insulating washer, after which the lower 35 nut can be tightened on the corresponding screw to serve as a lock-nut.

Thus arranged, the two screws 7 and 8 form terminals of the circuit and simultaneously clamp the two insulating plates and 40 the ends of the circuit wires firmly in position. One of the said screws, namely the screw 7 in the embodiment of the drawings, also extends through a perforation in one end of a contact member 13 made of a resilient metal (such as phosphor bronze) and so formed that its own resiliency will normally force its other end down upon the head of the companion screw 8. This contact member also has an arm 14 extending 45 laterally from its free end, so that this arm will overhang the lower insulating plate 5 but will be spaced from the latter by the thickness of the upper insulating plate and the added thickness of the screw 8.

50 To raise the contact member out of engagement with the screw 8 when the circuit is to be opened, I provide a member movable within the casing and having a portion adapted to be interposed between the arm 14 of the contact member and the lower insulating plate. For this purpose, I desirably employ an insulating head 15 in the form of a punching of hard rubber or fiber disposed vertically edgewise and corresponding 55 in height to the distance between the

lower insulating plate 5 and the cover 2 of the casing, so that this insulating head is slidably guided by the said cover and insulating plate. The head 15 is notched from the edge facing the nearer end 6 of the 70 casing so as to afford a lower wedge-shaped portion 17 adapted to be slid under the overhanging arm 14 to lift this arm sufficiently to bring the contact member 13 out of engagement with the head of the screw 8. 75

To operate the movable head 15 for this purpose, I fasten the same to a metal stem 18 extending slidably through a slot in the other end 19 of the casing and having in its exposed outer portion an eye 20 whereby 80 this stem may be connected to a brake lever or other means for actuating the switch by a pull on this stem in a direction which is towards the left in Figs. 1, 4 and 5 of the drawings. To prevent a lateral movement of the head 15, I also provide suitable means associated with it for slidably engaging the side walls 21 and 22 of the casing and for this purpose desirably employ a guide pin 23 driven tightly through a corresponding bore in the head 15 and extending through a corresponding bore in the stem 18. Thus arranged, the stem 18 with the head 15 and the guide pin 23 rigidly secured to the same form the operating member of my switch. 85 Then I also provide yielding means for normally holding this operating member in a predetermined position, desirably by slipping a spiral compression spring 24 over the stem 18 so as to interpose this spring between the end 19 of the casing and the head 15 on the operating member. 90

With the switch thus constructed for use on a normally open circuit, the spring 24 normally slides the operating member towards the left in Fig. 4, or until the insulating head thereon abuts against the wall 16, thereby causing the wedge 17 to lift the contact member off the head of the screw 8 as shown in Fig. 6. However, if the operating 105 member is pulled towards the left of Fig. 4 against the pressure of the spring, the resiliency of the contact member 13 will flex the latter downwardly into engagement with the head of the screw 8, thereby closing the circuit. This closing of the circuit occurs as soon as the operating member has been moved for a predetermined distance depending on the thickness and slope of the wedge portion 17 and any continued movement of the operating member in the same direction will not effect the operation of the switch. Consequently, my construction is particularly adapted for purposes where the extent 110 of the pull may be varied considerably. 115

To facilitate the assembling of the parts, I desirably fasten the contact member 13 first to the upper insulating plate 6 by a rivet 25, this being done while the contact arm is swung to a position corresponding to 120 125 130

that shown in dotted lines in Fig. 8. Then I insert the screw 8 and swing the contact member to its normal position with respect to the upper insulating plate, after which I 5 insert the companion screw 7 which extends through a perforation in the stationary end of the contact bar, so that this screw and the rivet 25 cooperate in preventing the contact bar from rotating about either thereof. 10 When the two screws are then slipped through the lower insulating plate, the lower head of the rivet 25 bears against the top of the lower insulating plate, so that the latter insulates this rivet from the bottom of the 15 casing. By thus forming a screw and contact assembly on the two insulating plates before slipping the latter into the casing, I simplify and facilitate the manufacture of the switch, as the resulting assembly can 20 readily be dropped into the case and clamped in position by affixing the insulating washers 10 and the nuts 9 to the screws.

The operating member is assembled by simply driving the guide pin 23 tightly 25 through a corresponding bore in the insulating head 15, slipping this pin through the corresponding bore in the bar 18 and riveting the latter to the insulating head by a rivet 27. The spring 24 is then slid over 30 the main portion of this bar, and the perforated end of the latter is slipped through the slot in the end 19 of the casing from the interior of the latter. By then moving the assembled operating member so that the 35 wedge portion of its insulating head will clear the arm on the contact member, the head portion can readily be swung down into its normal position, after which the cover plate is attached by the eyelets 3.

40 With the switch thus assembled, it will be evident that the wiring connections are conveniently exposed on the exterior of the switch so that the casing does not need to be opened for this purpose but can be left 45 closed at all times. In operation, the slot through which the stem 18 projects guides the outer end of the latter, while the head of the operating member is guided at its top by the cover plate and at its bottom by the lower 50 insulating plate or bottom lining and is also guided laterally by the sides 21 and 22 of the casing. Moreover, the upper insulating plate 6 may also be made of such a width as to engage one face of the head 15 so as to 55 form an additional lateral guide for the latter as shown in the drawings.

However, while I have illustrated and described my invention in an embodiment in which the retracting spring normally holds 60 the switch in a circuit-opening position and one including various desirable details of construction suitable for a particular purpose, I do not wish to be limited in these respects. Obviously, the switch of my invention might also be employed for other

purposes, while the construction and arrangement might be varied in many respects without departing either from the spirit of my invention or from the appended claims.

70 I claim as my invention:—

1. An electric switch including an elongated casing of rectangular section, an operating member movable longitudinally thereof and having a head slidably engaging two opposed longitudinal walls of the casing, and a guide pin fast upon and extending transversely of the head and slidably engaging the other two longitudinal walls of the casing.

75 2. In an electric switch, an elongated casing, an insulating lining for a longitudinal wall thereof, a pair of wire terminals mounted on the insulating lining, a resilient contact member fastened to one terminal and yieldingly forced by its own resiliency into engagement with the other terminal, and a separator of insulating material slidably disposed between the said insulating lining and the opposite longitudinal wall of 80 the casing and formed for forcing the contact member out of contact with the said other terminal when the separator is at the end of its slideable movement in one direction, the insulating lining having a shoulder 85 formation extending longitudinally of the casing for laterally guiding the separator.

90 3. A contact separating member for a switch having a pair of yieldingly engageable contacts, comprising as one element an insulating head having a wedge portion arranged for moving one of the contacts, and as another element a stem fast on the said head, and a guide pin fast on one of the 95 said elements.

100 4. A contact separating member for a switch having a pair of yieldingly engageable contacts, comprising a flat insulating head having a tapering notch at one end to provide a wedge formation, the wedge 105 formation being arranged for moving one contact away from the other, a flat stem fast on the head, and a guide pin fast with respect to both the head and the stem and extending transversely of both of the latter.

110 5. A contact separating member for a switch having a pair of yieldingly engageable contacts, comprising a flat insulating head having a wedge portion arranged for moving one contact away from the other, a stem fast at one end upon the head, a casing housing the said contacts and separator, and spring means continuously urging the separator in one direction and normally forcing the insulating head against one end 115 of the casing.

120 6. A contact assembly for an electric switch, comprising a pair of superposed insulating base members, a pair of circuit terminal screws each extending through 125

both base members and presenting heads on the upper member, a resilient contact strip clamped at one end against the upper base member by one of the screw-heads and having its other end bearing against the other screw head, and a rivet securing the contact strip to the upper base member at a point between the two screw heads, the rivet terminating above the lower base member. 10

Signed at Chicago, Illinois Feb. 18th, 1922.

THOMAS J. KERWIN.
